UNITED STATES PATENT OFFICE.

EARL M. RICHARDS, OF PITTSBURGH, PENNSYLVANIA, ASSIGNEE, BY MESNE ASSIGNMENTS, TO WESTINGHOUSE ELECTRIC & MANUFACTURING COMPANY, A CORPORATION OF PENNSYLVANIA.

IRONING MACHINE.

Application filed October 14, 1924. Serial No. 743,525.

My invention relates to ironing machines and has special relation to domestic ironing machines. It is closely related to the ironing machines constituting the subject matter of my co-pending applications, Serial No. 501,881 filed Sept. 20, 1921, and Serial No. 670,512 filed Oct. 24, 1923.

One object of my invention is to provide an ironing machine in which a roll is moved 10 toward a shoe by a toggle device.

Another object of my invention is to provide a clutchless ironing machine of an especially simple construction.

A further object of my invention is to 15 provide a toggle device that is motor-operated for moving one of a pair of ironing members towards the other and which is operable otherwise than by a motor for moving the former member away from the 20 latter.

A still further object of my invention is to provide an ironing machine in which many of the operating members are positioned on one casting whereby assembling 25 and shipping are facilitated.

A still further object of my invention is to provide an ironing machine made up of a minimum number of parts.

Other objects and advantages will appear 30 as the description proceeds.

Reference is now had to the accompanying drawings, in which

Figure 1 is a front elevational view of an ironing machine embodying my invention.

Fig. 2 is an end elevational view, as viewed from the right, of the machine shown in Fig. 1, the parts being illustrated with the ironing members disengaged.

Fig. 3 is an enlarged elevational view 40 similar to Fig. 2, of the upper portion of the machine showing the ironing elements engaged, parts of a standard being broken away to show inner construction.

Fig. 4 is an enlarged front elevational 45 view of the upper-right-hand end of the machine.

Fig. 5 is a plan view of the right-hand end of the machine.

Fig. 6 is an elevational view of the left-hand end of the machine, and

Figs. 7 and 8 are detail sectional views

of a device for locking the drive to and also unlocking it from the roll.

The machine illustrated as embodying my invention comprises a shoe 1, a feed-board 55 2, standards 3 and 4 supporting the shoe 1 and the feed-board 2, a roll 5, a casting 6, (Fig. 3) pivoted on the standard 4 and a motor 7 carried by the casting 6.

The roll 5 (Fig. 1) is provided at one end 60 with a disc 8, and at the other with a disc 10 each adapted to rotate upon a shaft 11 which projects from the roll at both ends.

The disc 10 is integral with a sleeve 12 (Figs 7 and 8) upon which a spur gear 13 65 is mounted for rotation. The spur gear 13 supports a device for communicating a drive to the sleeve 12. This device is similar to mechanism shown in my application filed October 24, 1923, Serial No. 670,512, and is 70 releasable by the operator in a manner hereinafter described. It comprises a detent 14 urged downwardly by a spring 15 against an annular ratchet 16 and having a slot 17 receiving a plunger 18 provided with 75 a shoulder 20 thereon adapted to be received in a recess 21. The plunger is urged in a direction toward the recess 21 by a spring 22. This device, which serves as a clutch, is supported in and constitutes part of the hub of 80 gear 13.

A bracket 23 (Figs. 3 and 4) is supported on the standard 4 and projects therefrom toward the spur gear 13. The bracket 23 has a pair of arcuate cams 24 and 25 formed 85 thereon. The roll 5 is movable in a manner hereinafter described from a position away from the shoe 1 to the position wherein it contacts with the shoe 1, or with articles to be ironed which are interposed between the roll 5 and the shoe 1. In the latter position, the rotation of the spur gear 13, in a manner to be hereinafter described, causes the plunger 18 to travel in a circle concentric with, and of the same curvature as, the arcuate 90 cams 24 and 25.

The shaft 11 is movable in a slot 26 in the standard 4 in a direction away from the shoe 1. The casting 6, which fits closely about the shaft 11 and permits rotative 100 movement thereof, is secured to the standard 4 by a pivot pin 27. The slot 26 is of such

shape as to permit the movement of the shaft 11 away from the shoe 1 and its travel about the pivot pin 27.

As shown in Fig. 3, the shaft 11 is provided with an opening in which a bolt 28 is slidable, the movement thereof being limited by a head 30. The bolt is screwed into an arm 31. A nut 32 is threaded on the arm and engages an end of a spring 33, the other end of which is in engagement with a member 34 pinned to the shaft 11 and removable therefrom. The arm 31 is secured by a pivot pin 35 to a second arm 36 that is rigid with a spindle 37 journaled in the standard 4. The arms 31 and 36 constitute a toggle. The left extremity of the shaft 11 is secured to a toggle 38 that is pivoted on a bracket 39 and limited in downward movement by a stop 40. At this end, the shaft 11 is slidable in a slot 41 in the bracket.

A lever 42 is secured on the spindle 37, and is adapted to engage, at its end, with a cap 43 into which the upper end of a section of a rod 44 is screwed. The cap 43 may be rotated and thus moved longitudinally of the rod for varying the effective length of the rod. The rod 44 is secured, by a detachable coupling 45, (Figs. 1 and 2) to a second rod 46, which is slidable in a guide 47 in the standard 4. The standard 4 is of two parts, separable along a line 48 adjacent the coupling 45.

It is apparent that the rods 44 and 46 may be readily disconnected into two separate parts, as may also the standard 4, and that, then, the lower part of the standard 4 together with the rod 46 may be handled as a single unit. This facilitates shipping and makes assemblage of parts convenient.

40 The rod 46 has a pin-and-slot connection 50 (Fig. 2) with the inner end of a pedal 51 pivoted on the standards 3 and 4. A spring 52, (Fig. 1) normally retains the outer part of the pedal in upper position.

45 The rod 44 carries an arm 53 having an arcuate face 54 adapted to engage a stud 55 on a cam 56 that is rigid with a spindle 57 journaled in the casting 6 and rigid with a segmental gear 58 that is adapted to mesh 50 with the spur gear 13. The cam 56 has a circular face that is adapted to engage a button 59 of a switch 60, of conventional construction, which exercises a permanent force tending to move the button 59 outwardly. The circular face is interrupted by a recess 61 which is adapted to permit the button 59 to move outwardly to a position in which the switch 60 is in its "off" position. A link 62 is pivoted at one end to the cam 56 and at the other is provided with a slot 63 receiving the pivot pin 35 at the knuckle of the toggle.

The switch 60 controls, through conductors 64, the motor 7.

65 The motor 7, as described, is secured to

the casting 6 and, through a shaft 65, drives worm 66 which meshes with a worm gear 67 having a spindle 68 journaled in the casting 6 and carrying a pinion 69 continuously meshing with the spur gear 13.

Operation with roll in contact with shoe.

When the parts are in normal operating relation, (Fig. 3) as when articles are being subjected to an ironing action by the roll 5 and the shoe 1, the motor 7, through the worm 66, the worm gear 67, the pinion 69 and the spur gear 13, drives sleeve 12, and through it the roll 5. A pressure is maintained between roll 5 and the shoe 1 by the toggles on both sides of the machine acting through spring 33 and the corresponding spring on the opposite side of the machine. Both nut 32 and the corresponding nut on the opposite side of the machine may be adjusted on the arm 31 and the arm 38, respectively. Thus, the pressure between the roll 5 and the shoe 1 may be varied. With the ironing elements engaged in ironing position, the toggles are located in stable positions because the lines of action of the springs are slightly under the spindle 37 and the corresponding spindle on the opposite of the machine and are held there by the stop 40.

Release operation.

To separate the ironing members, the operator depresses the pedal 51 and thus moves the rods 44 and 46 upwardly. This causes the cap 43 to engage the arm 42 and give rotative movement to the spindle 37. The arm 36 is thus swung upwardly.

After slight travel, the center of the pivot pin 35 passes above a straight line extending between the spindle 37 and the shaft 11. The spring 33 is then permitted to expand and the pivot pin 35 is urged upwardly by the action of the spring. The movement of the arm 36 is communicated to the shaft 11 which causes the toggle 38 to move upwardly at its knuckle, the movement of the toggle 38 duplicating the corresponding toggle movement at the other end of the machine.

The release of the toggle permits the downward movement of the roll 5 and the swinging of the casting 6 about the pivot pin 27. In the downward movement of the roll 5, the shaft 11 is guided, at one end, in the slot 41 and, at the other end, in the slot 26. The slots 41 and 26 determine the lowermost position of the roll 5. The full release position is shown in Fig. 2. The stoppage of the downward movement of the roll 5 is not attended with very considerable shock as the roll 5 is light in weight and the casting 6 is pivotally supported near its center of gravity.

As shown in Fig. 3, when the roll 5 is in

- ironing position, the cam 56 engages the switch button 59. After limited upward movement, the pivot pin 35 reaches the upper portion of the slot 63 in the link 62.
- 5 Further movement upwardly of the pivot pin 35 is communicated to the link 62 and the cam 56 is moved to permit the switch button 59 to move outwardly into the recess 61 in the cam 56, thus stopping the motor 7.
- 10 It should be noted that this separation of the ironing elements can be accomplished whether the motor 7 is operative or not.
- After the movement of the roll 5 away from the shoe 1, it may be desired to move 15 the roll in either direction for the purpose of arranging articles to be laundered thereon, or removing articles that have passed downwardly between the roll 5 and the shoe 1. To release the roll 5 from the shaft 11, 20 the operator rotates it manually toward the shoe 1. This causes the sleeve 12, Fig. 8, to rotate in the same direction, and the annular ratchet 16 acts upon the detent 14 and lifts it, permitting the plunger 18 to move outwardly under the urge of spring 22 and the shoulder 20 to seat in the recess 21. The seating of the shoulder 20 in the recess 21 25 operates to lock the detent 14 in retracted position and permits free rotation of the roll 5 in either direction.
- When the roll 5 is moved laterally toward the shoe 1 in a manner presently to be described, the plunger 18 is engaged with one of the arcuate cams 24 or 25 when the roll 5 reaches the end of its lateral movement. This engagement will occur as soon as the 30 roll 5 reaches its final position, if the position of the pin 18 rotatively with respect to the shaft 11 is such that one of the cams 24 and 25 is in its path of travel. If, however, the cams 24 and 25 are not interposed in the lateral path of travel of the plunger 18, slight rotation of the spur gear 13, through its driving connections, after the 35 roll 5 reaches the end of its lateral movement, rotates the plunger 18 into engagement with one of the cams 24 and 25. Either of these methods of engagement of the plunger 18 with one of the cams 24 and 40 25 moves the plunger 18 inwardly, releasing the shoulder 20 from the recess 21 and permitting the detent 14 to engage with the annular ratchet 16. The spur gear 13 is then operative to transmit driving force directly 45 to the roll 5.

Movement of roll toward shoe.

To move the roll 5 laterally toward the shoe 1, the operator depresses the pedal 51 and lifts the rods 44 and 46 upwardly. This 50 brings the arm 53 into engagement with the stud 55 and causes the rotation of the cam 56. By reason of the arcuate character of the face 54 of the arm 53, slight movement 55 of the stud 55 with respect to the arm 53 transversely of the machine is permitted. At the time of the engagement of the arm 53 with the stud 55, the switch button 59 is in its outer position, projecting into an end of the recess 61 of the cam 56. Slight movement of the cam 56 causes the depression of the switch button 59 and energizes the motor 7.

The energization of the motor 7 actuates the worm 66 which gives rotative movement 75 to the worm gear 67, the pinion 69 and the spur gear 13. After a slight further rotation of the cam 56 beyond the point where the depression of the switch button 59 is initiated, the segmental gear 58 is brought 80 into mesh with the spur gear 13. In case the top of the teeth on both gears strike, engagement will only be delayed a fraction of a second because the rotation of spur gear 13 which has already been started will 85 promptly cause it to pass to a position where free engagement between segmental gear 58 and spur gear 13 will be accomplished. The movement of the spur gear 13 is then transmitted to the segmental gear 58. After 90 the energization of the motor 7, and the engagement of the segmental gear 58 with the spur gear 13, the operation becomes automatic.

The motor 7 causes the rotative movement 95 of the segmental gear 58 in the manner described to move the link 62 downwardly and causes the arms 31 and 36 to exercise a toggle action, rotating the shaft 11 and causing the toggle 38 to operate to move the roll 100 5 against the shoe 1. The downward movement of the toggle knuckles causes the spring 33 and the spring of the toggle 38 to exercise pressure upon the shaft 11 which is transmitted to the roll 5 and the shoe 1. 105 The lowermost position of the toggle knuckles is determined by the stop 40 which is engaged by the toggle 38.

In this operation, the link 62 exerts force 110 upon the pivot pin 35 until the pin passes beyond a straight line extending from the spindle 37 to the shaft 11. At this time, the point of pivotal connection of the link 62 to the cam 56 is on a straight line running through the centers of the pivot pin 35 and the cam 56. Further rotation of the cam 56 causes a slight upward movement of the link 62. This upward movement is not transmitted to the pivot pin 35 as the slot 63 permits limited upward movement of the link with respect thereto. The segmental gear 58 has a slight rotative movement after the pivot pin 35 reaches its lowermost position. It then passes out of mesh with the spur gear 13.

No further movement is transmitted to the cam 56 while the roll 5 is in ironing position. During the rotative movement of the cam 56, which is incidental to the movement of the roll 5 into ironing position, the

face of the cam is maintained in contact with the switch button 59. When the movement of the cam 56 is arrested, the button 59 is still in contact with the face of the cam 56 but at a point adjacent to the recess 61.

The movement of the roll 5 toward the shoe 1 is transmitted by the shaft 11 to the casting 6 which is rotated about its pivot pin 27.

- 10 As illustrated in Fig. 8, if the gear wheel is disengaged from the sleeve 12 by the pawl 14 being held in raised position before the roll is moved towards the shoe, the pin 18, which is holding the pawl 14 in raised position, will engage one of the cam surfaces 24 or 25 and will be pressed inward against the spring 22 to release the pawl 14. The spur gear 13 will then be mechanically connected to the sleeve 12 to effect rotation of 20 the roll since the pawl 14 will now engage one of the teeth in the annular ratchet at the end of the sleeve 12. The arcuate cams 24 and 25 are supported on the bracket 23 secured to the standard 4.
- 25 The machine accomplishes, by the use of the segmental gear, the relative movement between the roll 5 and the shoe 1, which tends toward the general simplification of the machine, by accomplishing the ironing 30 functions with the utilization of a minimum number of parts and by constructions of the greatest simplicity.

The casting 6 may be removed from the pivot pin 27 and may also be removed from 35 the shaft 11 on the detachment of the member 34 which is merely pinned on the shaft, and the link 62 may be disconnected from the pivot pin 35. The casting 6, with nearly all of the operating members secured thereon, 40 may then be handled as an independent unit. This facilitates shipping. The combination of parts also makes assemblage convenient, as the casting and the associated parts may be treated as a unit for assembling purposes.

45 The invention is not limited to details of construction and the embodiment illustrated and described may be extensively varied and modified. For instance, a roll may be substituted for the shoe 1. Again, a hand-operated member may be used instead of the 50 pedal 51, if desired. A substantial range of equivalents is contemplated within the spirit of the invention and the scope of the appended claims.

55 I claim as my invention:

1. An ironing machine comprising a fixed ironing member, an ironing roll, means supporting said roll for movement toward, and away from, the fixed ironing member, a 60 support, an arm pivoted on said support, a second arm pivoted to said first-mentioned arm, and secured for limited sliding movement with respect to said roll, a spring on said second arm for biasing said roll to the

extreme limit of its connection with said 65 second arm, and means for actuating said arms adjacent to their point of pivotal connection for moving said roll toward said fixed ironing member.

2. An ironing machine comprising an 70 ironing member, a roll mounted for movement toward, and away from, said ironing member, a gear for rotating said roll, means for rotating said gear, toggle means for moving said roll toward said ironing member, a 75 gear meshing with the first mentioned gear, and means operative on the movement of said gears to cause said toggle means to exert a toggle action for moving said roll toward said ironing member. 80

3. An ironing machine comprising an ironing member, a second ironing member mounted for movement toward, and away from, the first mentioned ironing member, a toggle for moving said second ironing member toward said first mentioned ironing member, a member movable by an operator, means operative on one movement of said member for causing said toggle to move said second ironing member toward said first-mentioned ironing member, and means operative on a subsequent similar movement of said operating member for releasing said toggle to permit said second ironing member to move away from said first-mentioned 95 ironing member. 100

4. An ironing machine comprising an ironing member, a second member, a roll mounted for rotative movement on said second member, a gear for rotating said roll, 100 a motor on said second member for driving the gear, and means operative by said motor to move said second member and to swing said roll toward said ironing member.

5. In an ironing machine, the combination of an ironing member, a roll, a gear for rotating said roll, a member for supporting said roll and said gear for rotation, toggle means for moving said roll, said gear and said supporting member, a second gear adapted to mesh with the first-mentioned gear and mounted for rotation on said supporting member, a motor on said supporting member for moving said first-mentioned gear, and means connecting said second gear to said toggle means for actuating said toggle means on the movement of said gears by reason of their meshing relation to move said gears and said supporting member and swing said roll toward said first-mentioned 115 ironing member. 120

6. An ironing machine comprising an ironing member, a second ironing member, a member for supporting said second ironing member for rotative movement, a motor secured to said supporting member, and means operated by said motor for moving said supporting member and for moving said second

ironing member laterally relatively to the first-mentioned ironing member.

7. An ironing machine comprising an ironing member, a second ironing member, a member for supporting said second ironing member, means supporting said supporting member for pivotal movement, a motor on said supporting member, and toggle means operated by said motor for imparting pivotal movement to said supporting member. 10

8. In an ironing machine, the combination with a stationary ironing element and a movable ironing element, one of which is a roll, of toggle means for moving one element 15 to and from the other, said toggle means

consisting of a link pivoted on a stationary support and a second link including a spring pivoted between the first link and the movable ironing element, a gear for rotating the roll and means for straightening the toggle 20 means to move the movable member consisting of a segmental gear, an element for moving the segmental gear into engagement with the roll-rotating gear and a connection between the segmental gear and the toggle. 25

In testimony whereof, I have hereunto subscribed my name this sixth day of October, 1924.

EARL M. RICHARDS.
